UNITED STATES PATENT OFFICE.

GEORGE HILLARD BENJAMIN, OF NEW YORK, N. Y.

EVAPORATOR.

1,255,502.

Specification of Letters Patent. Patented Feb. 5, 1918.

Application filed March 30, 1917. Serial No. 158,513.

To all whom it may concern:

Be it known that I, GEORGE HILLARD BENJAMIN, a citizen of the United States, residing at New York, in the county and State 5 of New York, have invented certain new new and useful Improvements in Evaporators, of which the following is a specification.

My invention relates to the construction 10 of evaporators as designed for the purpose of obtaining substantially fresh water from salt water, in the most economical manner.

The accompanying drawings will serve 15 to illustrate my invention, in which Figure 1 is a vertical section through an evaporator. Fig. 2 is a cross section and plan view on the line II—II of Fig. 1. Fig. 3 is a front elevation with a portion of the door and casing broken away to show the coils of the 20 evaporator. Fig. 4 is a side view of the door, manifolds, coils and supporting mechanism for the door, etc., when detached from the casing.

In the drawings, 5 indicates the shell of 25 a condenser. The front of the shell has formed in it an opening 6, adapted to be closed by a door 7 which may be secured to the shell by means of bolts 8. Secured to the inner side of the door 7 are manifolds 30 9—10, to which are secured coils 11. Interposed between the manifolds are braces 12—13. Secured to the lower part of the door is a plate or casting 14. Projecting from the front of the plate or casting in a 35 downward direction, are arms 15, in which is mounted an axle 16, carrying rollers 17. Projecting from the front of the plate or casting 14 and in a backward and downward direction so as to partially inclose the lower 40 part of the casing, are arms 18 which carry short axles 19 on each of which axles is a roller 20.

It will be seen that the construction is 45 such that the arms 15 and 18, with rollers 17 and 20 acting in conjunction with the door 7, serve to support the manifolds 9—10 and coils 11 when the door and manifolds are removed from the casing, the whole 50 weight of the door, manifolds and coils being supported by the rollers 17 and 20, which are external to the casing; the advantage of this construction over prior constructions being that the means used to support the manifolds and coils are entirely exterior to 55 the casing, and therefore not subject to the heating and corroding effects of the tem-

perature and chlorin vapors set free within the casing, particularly in the case where the evaporator is used for separating fresh water from salt water. The connection of 60 the coils 11 to the manifolds 9—10 may be any which is known as useful with corresponding apparatus.

Connected to the manifolds, external to the casing, are pipes 21—22, by means of 65 which steam may be fed to the manifold 9 and coils 11, and condensed water carried from the manifold 10 out of the apparatus. To remove the coils from the apparatus, nuts 21^a and 22^a are removed from bolts 70 secured to the door 7, so that the pipes 21—22 may be removed from the manifolds; then the nuts on bolts 8 are released, when the door, manifolds and coils mounted on the rollers can be moved outward for cleaning, and conversely, inward, and the nuts 75 replaced on the bolts to secure the parts in position.

Connected at one side of the bottom of the shell, is a feed pipe 23 and a blow-off 80 pipe 24. 25 indicates a pipe through which any vapor set free within the evaporator, may be carried out of the evaporator.

Having thus described my invention, I 85 claim:

1. An improvement in an evaporating apparatus, comprising a containing shell having an opening therein, a door detachably secured over said opening, a heating element mounted on the door, and means for supporting the door and heating element located wholly without and independent of the casing.

2. An improvement in an evaporating apparatus, comprising a casing having an 95 opening therein, a door detachably secured over said opening, a heating element mounted on the door, the heating element formed of a plurality of manifolds mounted on the door, a plurality of heating coils extending between the manifolds, and supporting means for the door and heating element located wholly without and not connected to the casing.

3. An improvement in an evaporating apparatus, comprising a casing having an 105 opening therein, a door detachably secured over said opening, a heating element mounted on the door, supporting means for the door and heating element located wholly 110 without and not connected to the casing, said supporting means consisting of a mem-

ber connected to the door, a pair of arms projecting forwardly and downwardly from the member, a roller carried by each of the arms, a pair of arms projecting backwardly and downwardly from the member, and partially enveloping the casing, and a roller carried by each of the arms.

4. An improvement in an evaporating apparatus, comprising a casing having an opening therein, a door detachably secured over said opening, a heating structure mounted on the rear side of the door and projecting when the door is in position within the casing, and supporting rollers 15 for said door and heating structure located wholly without the casing.

5. An improvement in an evaporating apparatus, comprising an upright casing having an opening in the front thereof, a door 20 detachably secured over said opening, a heating element mounted on the door and projecting within the casing, and movable supporting means for the door and heating element secured to the lower part of the door 25 and located wholly without and not connected to the casing, whereby the door and the heating element may be moved into and out of the casing as desired.

6. An improvement in an evaporating apparatus, comprising a casing having an opening therein, a door detachably secured over said opening, a heating element mounted on the door and means for supporting and permitting movement of the 35 door and heating element comprising two

pairs of rollers, one pair having their axes located in a vertical plane in front of the door and the other pair in a vertical plane to the rear of the door, and said rollers located wholly without the casing.

40

7. In an evaporating apparatus, the combination of a casing having an opening therein, a heating element structurally independent of the casing and comprising a door, means for securing the door to the 45 casing, a plurality of manifolds, a plurality of heating coils extending between the manifolds, and means for carrying the weight of the door and heating element, both when the heating element is in the casing and out 50 of the casing, comprising two sets of rollers mounted on arms, one set located in front of the door and the other set to the rear of the door.

55

8. An improvement in an evaporating apparatus, comprising a casing having an opening therein, a door detachably secured over said opening, a heating element mounted on the door and projecting within the casing, a feed pipe, a blow-off pipe and 60 a vapor pipe connecting with the interior of the casing, and supporting means for the door and heating element located wholly without and not connected to the casing.

65

In testimony whereof, I affix my signature, in the presence of two witnesses.

GEORGE HILLARD BENJAMIN.

Witnesses:

HELEN E. KOELSCH,
HELEN E. MISCHNER.
